UNITED STATES PATENT OFFICE.

JESSE W. MARTIN, OF FRIENDSHIP, TENNESSEE, ASSIGNOR OF ONE-HALF TO SILAS MARTIN, OF FRIENDSHIP, TENNESSEE.

COIN SEPARATOR.

1,419,878.

Specification of Letters Patent. Patented June 13, 1922.

Application filed April 18, 1921. Serial No. 462,311.

To all whom it may concern:

Be it known that I, JESSE W. MARTIN, a citizen of the United States, residing at Friendship, in the county of Crockett and State of Tennessee, have invented certain new and useful Improvements in Coin Separators; and I do hereby declare the following to be a full, clear, and exact description of the invention, such as will enable others 10 skilled in the art to which it appertains to make and use the same.

The present invention relates to improvements in coin separators and has for an object to produce a compact apparatus for the 15 quick and efficient separation of heterogeneous coins into their various denominations.

It is another object of the invention to provide a machine which will effect this separation of coins in a minimum of time, 20 accurately and with the expenditure of little manual effort.

A further object of the invention lies in providing a simple, inexpensive device for carrying out the above described purposes 25 which will be of small size and yet have a comparatively great capacity for the coins to be separated.

With the foregoing and other objects in view, the invention will be more fully described hereinafter, and will be more particularly pointed out in the claims appended hereto.

In the drawings, wherein like symbols refer to like or corresponding parts throughout the several views,

Fig. 1 is a front view of an improved coin separator constructed according to the present invention;

Fig. 2 is a side view of the same;

Fig. 3 is a top plan view of the coin separator;

Fig. 4 is a vertical sectional view taken on the line 4—4 in Fig. 3;

Fig. 5 is a similar view taken at right angles on the line 5—5 in Fig. 4; and

Fig. 6 is a horizontal sectional view taken on the line 6—6 in Fig. 4.

Referring more particularly to the drawings, the device embodies generally a framework and a cabinet within the framework with operating means for causing the reciprocating and oscillating movement of the cabinet, within which are provided a number of coin trays having openings of varying sizes in their bottoms to permit a sifting

action of the coins and their subsequent separation into the respective trays.

The framework is composed of a base 1 from which extend front uprights or standards 2 and 3 and rear standards 4 and 5. 60 Beams 6 and 7 are secured between the pairs of front and rear standards, and cross rails 8 and 9 are secured between front and rear standards at the top of the framework. Guide rails 10 and 11 at the bottom, and 12 65 and 13 at the top are secured along the sides of the framework to receive lower and upper sets of rollers 14 and 15 respectively carried by the sides of the cabinet which is designated generally at 16. At its bottom the 70 cabinet 16 is provided with two sets of rollers 17 and 18 adapted to roll along the imperforate base 1.

The cabinet 16 is closed on all sides and also on the top and bottom and is accessible 75 through a door 19 hinged at the front as indicated at 20, and provided with a latch 21 pivoted at 22 on the front face of the door and adapted to slip in a catch 23 on the front of the cabinet adjacent the free edge of such 80 door. The latch 21 oscillates in a strap 24 affixed to the door 19 and is urged downwardly into contact with the catch 23 by a flat spring 25 also secured to the door. A turn button 26 having a cam portion 27 85 adapted to engage beneath the latch 21 is employed to lift the latch against the influence of the spring 25.

Within the cabinet are guide strips 28 and 29 placed one above another at suitable intervals, being so arranged to receive sliding drawers 30 which are provided in any suitable number, for instance six such drawers are shown in the drawings as provided to receive silver dollars, half dollars, quarters, 90 nickels, pennies and dimes in the order mentioned. These drawers or trays are formed with openings 31 in their bottoms of various sizes to agree with the coins that are intended to pass therethrough. For instance, 100 the openings 31 in the uppermost drawer or tray 30 are large enough to permit coins of every denomination to pass therethrough with the exception of silver dollars. Thus silver dollars will be caught in the upper 105 tray. In a similar manner the openings 31 of the next tray or drawer 30 will be large enough to permit passage of all coins except half dollars, separating out from the heterogeneous coins all coins fed into the machine 110.

being half dollars. Each of the trays is preferably formed with a knob 32 to permit of its ready withdrawal. In the top of the cabinet is secured a hopper 33 accessible for placing coins therein through the opening between the top rails 8 and 9 of the framework.

As shown in Fig. 5, a rack 34 is affixed to one side of the cabinet 6 and is adapted to 10 mesh with a mutilated pinion 35 on a shaft 36 journaled in a beam 37 affixed to a suitable part of the framework. The shaft 36 may be rotated manually through a crank 38 projecting beyond the exterior of the 15 framework. This rack and pinion are intended to advance the cabinet forwardly or outwardly toward the left as shown in Fig. 5.

A coil spring 39 connected between beams 20 40 and 41 secured respectively to the back of the cabinet 16 and the framework, serves to draw the cabinet rearwardly in the opposite direction when the mutilated pinion 35 moves out of engagement with the rack 25 34. Coil spring checks 42 and 43 are secured to beams 44 and 45 respectively carried at the rear end of the framework, and these spring checks or stops are arranged in the path of the upper and lower portions 30 of the cabinet 16. The lower stop 42 is preferably of a greater length than the upper stop 43, and the lower stop 42 is also preferably wound of larger turns and heavier spring material so that it will catch the 35 lower part of the cabinet and tend to oscillate or tilt the cabinet so that its upper rear end may strike the top check 43 which will of course tend to return the same in the opposite direction or tend to right the cabinet 40 net.

The lowermost portion of the cabinet is also provided with rails or sills 46 and 47 tending to close the base at this point to avoid the entrance of foreign material which 45 might otherwise get beneath the cabinet and impede the action of the rollers 17 and 18.

In use, a heterogeneous assortment of coins is dumped in through the hopper 33 and accumulates in the uppermost tray 30. 50 The crank handle 38 is then put in motion which causes the mutilated pinion to first engage in the rack 34 and shift the cabinet 16 outwardly toward the left in Fig. 5 until it reaches the limit of this movement, whereupon the pinion 35 will move out of engagement with the rack 34 and release the cabinet to the action of the return spring 39. This latter spring, however, having been disengaged by the outward movement of the cabinet 55 acts to violently draw such cabinet to the rear and brings the lower rear portion of the cabinet forcibly against the lower projecting check spring 42 resulting in the cabinet's being abruptly arrested.

60 The action is such as to tend to force

the cabinet off its balance and make it swing about the rear roller 18, the upper portion of the cabinet swinging back and striking the upper check spring 43. This latter spring will of course impart a rebounding movement to the cabinet restoring it in the opposite direction.

The cabinet, during all of this movement, rolls easily and responsively within the framework on the rollers 17 and 18, and 70 likewise the correct position of the cabinet is always preserved by the side rollers 14 and 15 coming in contact with the guide rails or sills, all the time yielding the greatest freedom of movement without any appreciable friction. This violent reciprocating movement and abrupt checking of the cabinet causes the coins to be shifted across the openings 31 in the trays so that such of the coins as are smaller than the openings may pass therethrough and fall into the next lower tray, where the operation is repeated and this action is only necessary for a few seconds before all of the coins will be properly assigned to their 80 various trays. The oscillating action afforded by the check springs 42 and 43 is very important inasmuch as it causes the bottoms of the trays to assume an inclined position creating a tendency in the coins 95 to slide therealong and thus be properly presented to the openings.

After the progress of the sorting has been discontinued, the door 19 is opened and the various trays may be drawn outwardly with 100 the coins separated into their various denominations. The empty trays are then replaced and the apparatus is in condition for subsequent action.

It is obvious that various changes and 105 modifications may be made in the details of construction and design of the above specifically described embodiment of this invention without departing from the spirit thereof, such changes and modifications being restricted only by the scope of the following 110 claims.

What is claimed is:

1. A coin separator comprising a framework, a coin receiving cabinet mounted for reciprocating and oscillating movement in the cabinet, means to move the cabinet in one direction in the framework, resilient means for drawing the cabinet in the opposite direction, and means for abruptly checking the movement of the cabinet in the latter direction and for causing the oscillation of the cabinet, substantially as described.

2. A coin separator comprising a framework, a cabinet mounted for reciprocating and oscillating movement therein, means to move the cabinet in one direction, resilient means for drawing the cabinet in the opposite direction, and a pair of resilient stops 125 130

- carried by the framework in the path of the cabinet for yieldingly checking the movement of the cabinet by said resilient means, said stops being of different lengths 5 to encounter the cabinet at different points and cause its oscillation, substantially as described.
3. In a coin separator, a framework, a coin receiving cabinet in the framework, 10 rollers carried by the cabinet and engaging the base of the framework to permit the cabinet to reciprocate and oscillate in the framework, guide means carried by the sides of the cabinet and engaging the sides of 15 the framework, means for moving the cabinet in one direction, other means for yieldingly tending to draw the cabinet in the opposite direction, and means for causing the abrupt arresting of the cabinet's movement 20 and for oscillating the cabinet, substantially as described.
4. In a coin separator, a framework, a cabinet mounted for reciprocating and oscillating movement therein, gear means carried by said cabinet, a co-operating mutilated gear carried by the framework and adapted to advance the cabinet in one direction, yieldable means for drawing the cabinet 25 in the opposite direction, and resilient stops for abruptly checking the movement of the cabinet, substantially as described.
5. In a coin separator, a framework, a cabinet mounted therein for movement in horizontal and vertical directions, means for shifting said cabinet in one horizontal direction, yieldable means for drawing the cabinet in the opposite horizontal direction, and stops for checking the last mentioned movement of the cabinet and for also causing the vertical tilting of the cabinet, substantially as described.
6. In a coin separator, a framework, a cabinet therein mounted for reciprocating and oscillating movement, a rack carried by the side of said cabinet, a mutilated pinion carried by the framework and adapted to mesh with said rack, operating means for the pinion extending on the exterior of said framework, guide means for the cabinet in said framework, resilient means for drawing the cabinet in an opposite direction after being advanced by said pinion, and resilient stops for engaging the upper and lower portions of the cabinet and for causing the tilting of the same, substantially as described.

JESSE W. MARTIN.
